UNITED STATES PATENT OFFICE

158,065

COMBINED HAIR CURLER AND COMB

Nellie I. George, San Francisco, Calif.

Application May 14, 1949, Serial No. 2,646

Term of patent 7 years

(Cl. D86—10)

To all whom it may concern:

Be it known that I, Nellie I. George, a citizen of the United States and a resident of San Francisco, in the county of San Francisco and State of California, have invented a new, original, and ornamental Design for a Combined Hair Curler and Comb, of which the following is a specification, reference being had to the accompanying drawing, forming a part thereof.

The essential features of my design are shown in full lines in the drawing.

I claim:

The ornamental design for a combined hair curler and comb, substantially as shown, and described.

NELLIE I. GEORGE.
